UNITED STATES PATENT OFFICE.

ALMER D. COE, OF CHICAGO, ILLINOIS.

WATCH-CASE.

SPECIFICATION forming part of Letters Patent No. 269,386, dated December 19, 1882.

Application filed July 27, 1882. (No model.)

To all whom it may concern:

Be it known that I, ALMER D. COE, of Chicago, in the county of Cook and State of Illinois, have invented certain new and useful Improvements in Watch-Cases for American Watch-Movements; and I do hereby declare that the following is a full, clear, and exact description thereof, reference being had to the accompanying drawings, and to the letters of reference marked thereon, which form a part of this specification.

This invention relates to features of construction in cases for American watches, having for their object to render the cases interchangeable for the two principal classes of American stem-winding movements known to the trade, and constituting the greater part of the watches kept for sale in this country. For the purposes of this description, and with reference to these features of their construction which are concerned in this invention, American watch-movements will be divided into two classes—to wit, the Waltham class and the Elgin class—each of which classes, however, embraces other movements than those made at Waltham or Elgin. Movements of the Waltham class are distinguishable with reference to this improvement in cases mainly by two features—viz., first, as having the winding-square fixed to the first or horizontal pinion-shaft of the winding mechanism in the movement, and arranged to protrude beyond the margin of the movement opposite the figure 3 of the dial, and by having the protruding end of the hand-setting lever located opposite the figure 5 on the dial. Movements of the Elgin class have the horizontal pinion-shaft of the winding mechanism located at the same circumferential point in the movement as the Waltham class; but instead of having a square fixed thereto the said pinion-shaft is socketed to admit a square winding-pin, and the setting-lever protrudes at a point a little beyond the dial-figure 5. Two classes or lines of cases, properly notched and otherwise fitted to immediately receive these several movements, have been provided, those for the Waltham class having a socketed winding-stem to receive the square of this class of movements, and those for the Elgin class having a square winding-pin fixed to the winding-stem, adapted

to enter the socketed pinion-shaft of the movement. Each class of cases, also, has the notches in the bezel and in the bezel-snap on the "case-center" appropriately located for the particular class of movements for which the case is intended. A dealer having movements of both classes in stock has thus needed to also carry two separate lines of cases, and, as the styles and qualities of such cases are various, to keep a desirable assortment has required a considerable investment in this single class of goods. By my invention, which, as above stated, is intended to provide a case adapted to receive a movement of either class, the investment necessary to afford the same selection as to styles or quality is reduced one-half; or by the same investment a much more extended assortment of cases may be kept on hand.

One feature of construction which distinguishes my invention for the purpose above stated is the combination, with the case-center and connected parts, of a bezel having a suitable notch for the setting-lever, and adapted to be set in either one of the two different positions required by the two mentioned classes of movements.

Another feature of my invention consists in constructing cases for both classes of movements with a square socket in the winding-stem, and providing a removable square pin which will be used with the socketed winding-pinions of the Elgin class of movements, but which will be removed for the reception of the fixed square pin on the Waltham class of movements.

These and other features of my improved construction will be better understood by reference to the drawings, in which—

Figure 1 is a plan view of a watch-case containing my invention, showing the "front back" lifted and the bezel removed. Fig. 2 is a fragmentary section of a watch-case having my improvements, taken through the axis of the pendant and transverse to the center and backs. Fig. 3 is a plan view of the bezel of my improved watch-case, showing its lower edge uppermost. Fig. 4 is a fragmentary plan view of a movement, showing the protruding winding-square of the Waltham class and the several positions of the hand-setting levers in both classes of movements. Fig. 5 is a side eleva-

tion of the winding-pinion of the Waltham movement, having a permanent square winding-pin rigid therewith. Fig. 6 is an axial section of the socketed winding-pinion of the Elgin class of movements. Fig. 7 is a fragment of the case rim or center, in side elevation, showing the broad notch cut in the bezel-flange.

A is the case-center. B is the bezel. C is the front back. D is the pendant. E is the winding-stem or "key-pipe." F is the head of the lock-spring. G is the spur of the fly-spring. H is the removable winding-square of my improvement. I is the annular flange or shoulder on the case-center, called the "bezel-snap." J is the similar outer flange or shoulder on the center, called the "back-snap." L is the steady-pin. M is the notch in the bezel-snap for the accommodation of the hand-setting lever. M' is the notch in the bezel for the same purpose. N is the winding-pinion of the Waltham class of movements, and n the square thereon. O is the winding-pinion of the Elgin class of movements, and o the socket therein. P is the setting-lever of the Elgin class of movements, and R is the setting-lever of the Waltham class.

It is understood that the winding-pinion of the movement, when the latter is placed in the case, always occupies the position directly opposite the pendant D. Provision must therefore be made in an interchangeable case at two points for the several setting-levers P and R of the two several classes of movements above mentioned. As said setting-levers differ in position in the two movements only very slightly, provision is made in the center A for the admission of either of them by cutting the notch M, Fig. 1, in the bezel-snap I, said notch M being of sufficient width and properly located 40 to take in either one of the levers P and R.

In the bezel B the necessary notch M' for the accommodation of the setting-lever is, however, made of the usual width or only sufficient to accommodate either lever, which levers are usually of about the same width in both classes of movements. Thus, providing but a single notch in the bezel for the admission of the setting-lever, it is necessary to so construct the bezel in other respects that it may be applied 50 to the bezel-snap on the center in either of the two positions required by the particular movement present in the case. To enable this to be done several modifications of the bezel and of the parts in the case concerned therewith are necessary. Thus it is usual to notch the bezel either on its lateral edge or on the bottom, or both, to make room for the head F of the lock-spring. It is also customary to cut the bezel opposite the back-hinge. Sometimes 55 the bezel is also notched to give play to the fly-spring spur G, and elsewhere for the purpose of accommodating the case-spring screw-heads when these are not flush with the center. It is always notched to admit the steady-pin. In my improvement I dispense with all these notches and cuts of the bezel, except those for the setting-lever and steady-pin, and

for the latter or steady-pin two notches are provided, one of which will be used when the case contains a movement of the Waltham 70 class and the other of which will be used when the case contains a movement of the Elgin class, said notches being so situated as to bring the setting-lever notch M' in the proper position according to the requirements of the 75 movement present in the case.

The notches for the accommodation of the case-spring screws may of course be easily obviated, as is now frequently done, by simply setting the heads of these screws flush with the 80 case-center. The other notches—namely, those for the lock-spring case, hinge, and fly-spring spur—may also manifestly be dispensed with by so enlarging the case-center as to give place for the parts which usually encroach upon the 85 bezel and make these notches or cuts therein necessary. Such diametrical enlargement of the case is, however, objectionable, and I find that it is not strictly necessary. To effect the 90 object without such enlargement I make the following changes: First, the bezel is made narrower on its lower edge or face, B', which is in part or wholly effected by making the bezel with a universal thumb-notch or annular recess, b, in its lower outer edge, as shown in 95 Figs. 2 and 3; second, the lock-spring head F is set outward in the case-center slightly farther than common, which may be accomplished by increasing the depth of the inner recess within said center at the point opposite the pendant, and by giving the case-spring a slight deflection in its curved or circular part near the head F, so as to set outward into the deepened recess described, but more particularly by so forming the inner angle, f, of said head, 100 as shown, that when the spring is thrust inward to release the back of the case said angle enters the recess b of the bezel. The upper edge of the lock-spring head F is also adapted to recede without striking the bezel in opening 110 the case, as clearly indicated in the sectional Fig. 2. The case-spring spur finds room for its necessary movement in the narrowing of the bezel at its base or lower surface, as described. 115

The two notches provided in the bottom edge of the bezel for the steady-pin L and intended to be alternatively used according to the requirement of the movement present in the case are shown at L' and L'', Fig. 3, being located at a 120 distance apart from center to center corresponding with the distance from center to center of the setting-levers P R, Fig. 4.

In watch-cases adapted for only one class of movements, as heretofore made, the notch 125 for the setting-lever often extends downward through the bezel snap or flange I on the center, and also into or part way through the back snap or ledge J. If the proposed wide notch M, Fig. 1, were to be made to extend into the 130 back-snap, as described, there would of course be left a space at one side of the setting-lever of either movement, beneath the lower edge of the bezel, through which dirt might be admitted

to the movement. In order to avoid this objectionable result, I make the back-snap J shallower than is commonly done, so that the entire cut M will be contained in the bezel-snap I, 5 by which means obviously the bezel will close the space at the side of the setting-lever. If preferred, the usual height or depth of the back-snap J of the case-center may be preserved by lowering the surface of the center exterior to 10 said snap, or, in other words, by making the center slightly thinner between the edges of the case-backs. If this is done, the same space will be preserved within the case by extending the front or top back to a degree corresponding 15 with the reduction in the thickness of the case-center, as suggested.

To provide for the difference between the two classes of movements with respect to the winding devices, all winding-stems E of my 20 improved interchangeable cases are provided with the socket e, made of suitable size to admit the square n of the Waltham class of movement, and a removable square pin, H, Fig. 2, is provided, fitted at one end to be set firmly 25 in said square socket e of the winding-stem and at the other end made slightly smaller, so as to fit the corresponding socket o in the winding-pinion shaft O of the Elgin class of movements. The difference in size between the opposite ends of the removable square H is owing 30 to the fact that as now constructed the socket o of the Elgin winding-pinion shaft is a trifle smaller than the square n of the Waltham pinion-shaft N. Of course, if a change 35 shall be made in either class of movements, so as to make the dimensions of these parts to correspond, there will thereafter be no necessity for making the removable pin H otherwise than of uniform diameter. The inequality now 40 required may, if preferred, be obtained by making the opposite ends of said square pin unequally tapering. This feature of unequal thickness of the square pin H, which is used only with the Elgin movement, perfectly prevents 45 said pin from becoming detached from the socket e of the winding-stem and falling through the continuous socket or hole o of the shaft O into the movement. Should said socket o be enlarged to correspond with the 50 size of the socket e, other provision may be required to prevent the detachment of removable square pin H from the socket of the winding-stem E—as, for example, a small screw entering the side of the winding-stem and engaging a 55 notch in the square H similar to the screw which holds the winding-stem to the pendant.

There is a slight difference between the two classes of movements mentioned in respect to the distance from the supporting flange or 60 shoulder on the movement and the axis of the winding-pinion, the socket o of the Elgin class being slightly farther from or below said supporting-flange of the movement than the winding-square n of the Waltham movement. This, 65 however, does not operate as an obstacle to the success of the interchangeable case, since the difference is so slight that the winding-

stem, having ordinary and reasonably free movement within the pendant, will connect properly with the winding device of either 70 movement; but, if desired, the pendant-axis may be located at a point equally above the axis of the Elgin winding socket and below the winding-square of the Waltham. The ordinary and desirable freedom of movement on 75 the part of the winding-stem then insures perfect operation of the connecting devices above described. The Waltham watch sits a little higher in the case-center than the Elgin class of movements, and the interchangeable case 80 therefore requires to be made so as to give room in this direction for either movement. The differences last mentioned are all very slight, and require no modification of the case as above described to suit both classes of 85 movements that will in any manner distinguish the case to the eye. One other fact should be mentioned—namely, that the Elgin class of movements are provided with a steady-pin arranged to project radially opposite the dial, 90 Fig. 11, and in position to enter a corresponding hole in the bezel-snap of the case. In the interchangeable case described this hole is of course provided for said steady-pin. It will occur to many that the notch for the setting- 95 lever may be left uncut in the bezel of otherwise ordinary construction; but I wish it to be understood that a case provided with the broad notch M in the bezel-snap contains my invention whether the bezel be notched and 100 of the movable description herein set forth or not. It will also occur to case-makers that, a movable bezel being provided, having a notch, M', and two steady-pin notches, L' L'', the notch M may be left uncut, and that a suitable narrow notch may be cut in the bezel-snap I by the watch-maker for the accommodation of the setting-lever. I also wish it understood that such uncut bezel-snap is included in my claim 105 for the combination, with the case-center, of the movable bezel B.

While I have spoken of the steady-pin L and the notches L' and L'' therefor in the bezel as being present in my improved interchangeable case, and while I greatly prefer that said 115 steady-pin and bezel-notches shall be used, it is possible to dispense with them in a movable bezel without departure from my invention. In this case the setting-lever notch M' will serve as a guide to the position of the bezel. 120

The second clause of the appended claim is intended to cover the construction of the case and movable bezel without respect to the presence of the steady-pin and notches.

The feature of the wide notch M may obviously be applied to open-faced watches in 125 which the flange I, above described as a bezel-snap, is present only as a finish.

I am aware that watch-makers have sometimes fitted a socketed winding-stem to an 130 Elgin case by driving a permanent plug into the socket of the winding-stem and squaring its protruding end to fit the socket o. This does not anticipate my invention, for the rea-

son that such plug has not thus been inserted with a view to its removal or as a feature in an interchangeable case.

I claim as my invention—

- 5 1. In a watch-case, the combination, with the case-center having the back snap or ledge J depressed to allow the setting-lever of the movement to project above the same, of an adjustable bezel contrived to clear the case-springs without being notched for the purpose, and provided with the setting-lever notch M' of the usual width, whereby said bezel may be set in the position called for by either movement present in the case, substantially as described.
- 10 2. In a watch-case interchangeable for the two classes of stem-winding movements mentioned, the combination, with the case-center having the steady-pin L, of an adjustable bezel provided with notches M', L', and L'', and contrived to clear the case-springs, whereby it is

adapted to be set in either of the two positions called for by the location of the hand-setting levers of said classes of movements, substantially as described.

25

3. In an interchangeable watch-case, a center having the ledge J depressed and provided with the broad notch M in the flange I, in combination with an adjustable bezel, substantially as and for the purposes set forth.

30

4. In combination with the case-center, the adjustable bezel provided with a continuous thumb-notch, and the catch-spring arranged to work within the thumb-notch of the bezel, substantially as described.

35

In testimony that I claim the foregoing as my invention I affix my signature in presence of two witnesses.

ALMER D. COE.
